LOOP CONTROL MECHANISM

Filed Feb. 6, 1922

FIG. 1.

FIG. 2.

FIG. 3.

UNITED STATES PATENT OFFICE

CAMILLE A. SENTOU AND ETIENNE JACQUET, OF FORT LEE, NEW JERSEY, ASSIGNEES
TO EASTMAN KODAK COMPANY, OF ROCHESTER, NEW YORK, A CORPORATION OF
NEW YORK

LOOP-CONTROL MECHANISM

Application filed February 6, 1922. Serial No. 534,342.

This invention relates to film apparatus having a loop control mechanism. One object of the invention is to provide such a mechanism which will maintain the size of the loop within the desired limits automatically. Other objects will hereinafter appear.

In the accompanying drawing:

Fig. 1 is a side elevation, certain parts being in section, showing a specific embodiment of our invention;

Fig. 2 is a fragmentary side elevation showing the loop controlling parts in a position differing from that in Fig. 1;

Fig. 3 is a top plan view of the apparatus;

Fig. 4 is a horizontal sectional view of the brake mechanism;

Fig. 5 is a detail side elevation of the adjustable arm of the brake;

Fig. 6 is a perspective view of the friction member of the brake.

Apparatus has come into use in which motion picture film is automatically and continuously moved through various fluid treating baths and finally dried. In Patent No. 1,385,403, July 26, 1921, we have disclosed a propelling means for the film in such apparatus, this means including a system for controlling the lengths of the film loops. When the film issues from the drying cabinet, it is desirable to maintain a loop the size of which is kept within definite limits. We have found that this object can be obtained by embodying the principle disclosed in our prior patent in a specifically different loop controlling system. Instead of moving the propelling means, such as rollers, at a constant speed, and shifting the film to portions of the rolls of different diameters, we have found that proper control can preferably be obtained by varying the speed of the propelling means or rolls themselves. While we shall illustrate this improvement in connection with a film treating apparatus, the inven-

tion is not limited thereto, except as indicated in the appended claims.

Referring to the drawing, 1 indicates conventionally a fragmentary section of a fluid treating apparatus, such, for example, as a drying cabinet. The film F passes over the roll 2 through a slot in the cabinet and over the roll 3, from which it is advanced into a downwardly extending loop containing the flanged roll 5, said loop terminating at the rolls 6 and 7. Of the latter, 6 is an idler roll, while 7 is a driven roller, which moves the film between it and roll 6 in a direction to remove it from the loop and feed it to hub 8 which, with its wound film, rests upon and is moved by rolls 11-12. These may be driven in any suitable manner. We have indicated conventionally a belt 13 passing over a pulley 10 and pulleys 11' and 12', the latter being connected with the rolls 11-12, while pulley 10 is driven by motor 15, the base of the latter resting upon the support 4. Roll 3 can be driven in the same way as the similar roll 7 in our earlier Patent 1,385,403, July 26, 1921, for "Machine for treating photographic moving picture films," by means of a bevel gear 60 on its shaft 61 meshing with a bevel gear 62 on the main drive shaft 63 of the fluid treating apparatus 1, driven from the main motor 70 (not shown) of said apparatus. This drives the roll 3 at the relative peripheral speed hereinafter described,—namely, substantially the same peripheral speed as the normal adjusted peripheral speed of roll 7. One effect of roll 5, which is not fully counterbalanced, as hereinafter explained, is to hold the film F in driving contact with roll 3; but any of the known expedients for insuring such contact can be used such as the one disclosed in our hereinabove cited patent.

The propelling roll 7 is mounted on shaft 25 which turns in bearing 26 on support 4. This shaft is rotated by means of pulley 28

16 driven through belt 14 from motor 15. Around the shaft 25 is arranged a brake mechanism which may be of any usual form adapted to this location. We have indicated by way of example a casing 27 threaded at 28 to receive a threaded collar 29 having a tapered bore 33 at one end which engages the tapered fingers 34 of friction member 35, said fingers being formed by slots 37 in said member. The collar 29 has attached to it, by means of screws 32, a disk shaped portion 31 of control arm 17. As is shown most clearly in Fig. 5, the angular relation of 17 to collar 29 can be varied by adjusting the bolts 32 in slots 32'. The disk has in its center an opening which clears shaft 25, as does collar 29 at the end of member 17. Opposite to the disk 31 there is located on 17 a transverse slotted portion 40 through 20 which passes a vertical cord or other suitable flexible element 20.

Cord 20 is connected at its lower end to an eye 23 on stirrup 24, which carries the freely rotating roll 5. At its upper end cord 25 passes over idler roll 22 and thence downward to a counterweight 21. The latter is preferably somewhat less in weight than the roll 5, so that said roll has a tendency to move downward under the force of gravity 30 to extend the film loop and rest upon the bottom of it. On the cord 20 are fastened, in any preferred manner, contact elements or buttons 18 and 19. These are spaced apart, 18 being above the slotted member 40 35 of control arm 17, while button 19 is below said control member.

In operation, the film F moves through the fluid treating apparatus and out of the dryer at a speed which is found best for 40 such treatment. Since it is advanced to the loop at this speed, it is necessary that it be removed from such loop at substantially the same speed to keep the loop size within limits. Roll 7 will tend to rotate fast 45 enough to remove the film from the loop, so as to keep the latter approximately constant. In practice, variations in the constancy of the film speed and, therefore, in the length of the loop tend to occur. The 50 disk 31 is so adjusted initially by means of bolts 32 and slots 32' that, when the member 17 is substantially horizontal, collar 28 will press to the right amount on fingers 34 on friction member 35 to restrain the shaft 25 55 down to the correct speed, the belt 14 slipping on pulley 16 slightly if necessary.

As will be seen from the drawing, the peripheral speed of rolls 11 and 12 will be the same as that of roll 7 when the latter is 60 moved at its maximum speed without slipping of belt 14 on pulley 16. But when the speed of roll 7 is lessened by the brake and belt 14 slips on pulley 16, film F will be under some tension as it enters the coil on 65 hub 8, and consequently slippage occurs at

the frictional points of the train 10, 13, 11', 12', 11, 12, which transmits rotation to the film coil on said hub 8.

If the loop lengthens, it will, when it reaches a limit, lower the roll 5 and consequently pull down the rope 20 until contact 18 engages control member 17 and presses the latter downwardly, as indicated in dotted lines in Fig. 2. This rotates collar 29 in a direction to lessen the pressure on fingers 34 of friction member 25. Of course, the friction member 35 is always substantially stationary, due to its large surface contact with casing 27. This lessens the brake on shaft 25 and accelerates slightly the rotation of 75 the latter. When the shaft 25 increases in speed, roll 7, which moves therewith, will turn more rapidly and temporarily remove film from the loop faster than it is advanced to said loop. This shortens the loop and raises the roll 5, thereby lifting the contact 80 18 from the member 17. The latter may be biased towards a horizontal position by means of weak springs,—not shown, but this is not absolutely essential.

If, on the other hand, the loop becomes temporarily shortened to its smaller limit of size, the roll 5 will be raised so far that contact 19, pulled upward by counterweight 21, 90 will contact and raise control member 17, thereby turning collar 29 in a direction to compress fingers 34 and increase the braking action on shaft 25. This slows down the latter, so that film is advanced to the loop faster than it is removed from it, thereby 95 lengthening the loop until roll 5 descends sufficiently to bring contact 19 away from control member 17.

While we have shown the apparatus as 100 adapted for the handling of unperforated film, the rollers being flanged, it will be evident that perforated film could likewise be handled without any modification. While we do not prefer it, the apparatus could be furnished with sprockets to engage perforated film, but this would limit the scope of such modification to the handling of perforated stock, whereas the preferred embodiment will handle both kinds of film.

Having thus described our invention, what 110 we claim as new and desire to secure by Letters Patent is:

1. In a film developing apparatus, the combination of: a drive roller; means for rotating said drive roller; a driven floating 120 roller, there being a film wound around said drive and driven rollers; means for controlling the rate of rotation of said drive roller, said control means having a brake arranged to engage said drive roller; and a member 125 energized by movement of said floating roller relative to said drive roller to actuate said control means, thus operating said brake.

2. In a film developing apparatus, the combination of: a drive roller; means for 130

rotating said drive roller; a driven floating roller arranged below said driver roller, there being a film wound around said drive and driven rollers; means for controlling the 5 rate of rotation of said drive roller; and a member energized by movement of said floating roller relative to said drive roller to actuate said control means so that the rate of rotation of said drive roller is reduced 10 when said floating roller moves toward said drive roller.

Signed at New York, New York, this 18th day of January, 1922.
